& Signal Company, Swissvale, Pa., a corpora-
tion of Pennsylvania

Application January 28, 1943, Serial No. 473,792

9 Claims. (Cl. 246—38)

Our invention relates to approach control apparatus for use in railway signaling systems of the coded track circuit class, and particularly to improved means for approach controlling various signaling functions without the use of line wires.

It is an object of our invention to provide improved apparatus of the type described which employs a feed-back detector relay of the stick polar type, and which is arranged so that the alternating current cab signal control energy is supplied to the section rails over a circuit independent of the feed-back relay.

Another object of the invention is to provide improved apparatus of the type described which is arranged so that energy stored in the track ballast as a result of the supply of impulses of master code to the rails of a track section will not interfere with operation of the feed-back detector relay.

A further object of the invention is to provide improved apparatus of the type described which includes means for delaying response of the feed-back detector relay to energy supplied thereto from a local source to thereby substantially equalize the periods in which the contact of this relay is in its normal and its reverse positions.

Other objects of the invention and features of novelty will be apparent from the following description taken in connection with the accompanying drawing.

We shall describe one form of railway signaling apparatus embodying our invention, together with a modification thereof which we may employ, and shall then point out the novel features thereof in claims.

In the drawing Fig. 1 is a diagram of a section of railway track equipped with track circuit apparatus embodying our invention, and

Fig. 2 is a fragmentary diagram showing a modification which we may employ.

Similar reference characters refer to similar parts in each of the two views.

In practicing our invention we provide the feed-back detector relay with two windings. A contact of the associated coding relay, when released, connects one of these windings across the section rails, while the impulse of feed-back energy supplied over the section rails to this winding causes the relay contact to be moved to one of its positions. When the coding relay contacts are picked up, the track battery and track transformer are connected across the section rails independently of the feed-back relay track winding, while a contact of the coding relay estab-

lishes a circuit to supply energy from a local source of direct current to the other winding of the feed-back detector relay and thus cause the relay contact to be moved to its other position.

5 Referring to Fig. 1 of the drawing, there is shown therein a section of railway track having track rails 1 and 2 over which traffic normally moves in the direction indicated by the arrow, that is, from left to right. The track rails of each section are separated from the rails of the adjoining sections by insulated joints 3 in the usual manner.

The equipment at the entrance end of the track section may be arranged in any manner well known in the art, but it is preferred to arrange 10 this apparatus in the manner shown in Letters Patent of the United States No. 2,286,002, granted to Frank H. Nicholson on June 9, 1942.

The equipment at the entrance end of the track 15 section includes a track relay TR, a decoding transformer DT, an impulse relay IR, an auxiliary relay H, and a battery FB. The track relay TR is of a type the contacts of which when released become picked up on the supply of energy of one polarity only to the relay winding. The relay H may be employed in the usual manner to control the supply of coded energy to the rails of the adjacent section in the rear and to control a signal, not shown, at the entrance to the section.

This invention is concerned with the arrangement of the equipment at the exit end of the track section. This equipment includes a feed-back detector relay K, an approach relay AR, a coding relay CR, a track transformer TT, and a track battery TB.

The detector relay K is of the stick polar type and its contact when moved to either of its two positions will remain in that position until a winding of the relay is supplied with energy effective to move the relay contact to its other position.

The coding relay CR is provided with contacts which are continuously picked up and released at one or another of a plurality of different rates depending on traffic conditions in advance. One means for controlling the relay CR is shown in Fig. 5 of Letters Patent of the United States No. 2,174,255 granted to Herman G. Blosser.

The approach relay AR controls the supply of energy to the track transformer TT from a suitable source of alternating current, not shown, the terminals of which are designated BX and CX. 55 The relay AR may also be employed to control

lighting of a signal, not shown, for the adjacent section in advance.

The equipment at each end of the track section includes a suitable source of direct current, not shown, the terminals of which are designated B and C.

The equipment is shown in the condition which it assumes when the track section is vacant. When contact 10 of coding relay CR is in its picked-up position, it interrupts the circuit of the track winding 11 of relay K, and connects the track battery TB across the section rails in series with the secondary winding of the track transformer TT and the current limiting resistor 12. The track battery is connected with the section rails in such manner that the positive terminal of the battery is connected to track rail 1. As the section is assumed to be vacant, master code energy from the track battery flows from the positive terminal of the battery over rail 1 through the track relay winding from its left-hand to its right-hand terminal, over back contact 14 of relay IR, track rail 2, front contact 10 of relay CR, resistance 12, and track transformer secondary winding to the negative terminal of the battery.

The energy from the track battery flowing through the winding of the track relay TR causes the contacts of the relay to pick up. On picking up of the track relay contacts there is a change in energization of the primary winding of the decoding transformer, and energy is induced in the transformer secondary windings. Energy from one of these windings is rectified by a contact of the track relay and is supplied to the relay H. Energy induced in the other secondary winding of the decoding transformer is supplied to the impulse relay IR. The relay IR, however, is of a type the contacts of which become picked up when energy of one polarity only is supplied to the relay winding, and the various parts of the equipment are arranged so that the impulse of energy supplied from the decoding transformer DT to the relay IR on picking up of the track relay contacts is of the polarity which is ineffective to pick up the contacts of relay IR. Accordingly, on picking up of the track relay contacts, the contacts of relay IR remain released and continue to connect the track relay across the section rails.

In addition, on picking up of the contacts of relay CR, its contact 15 establishes the circuit to supply energy from a local source to the local winding 16 of relay K. This energy flows through the winding 16 in the direction effective to move the contact 18 of the relay to its right-hand or reverse position in which it interrupts the circuit of the relay AR.

On release of the contacts of relay CR contact 15 interrupts the circuit of winding 16 of relay K, while contact 10 interrupts the circuit of the track battery and connects the track winding 11 of the relay K across the section rails.

When the circuit of the track battery is interrupted, the contacts of the track relay TR release and there is a change in energization in the primary winding of the decoding transformer so that an impulse of energy is induced in each of the transformer secondary windings and is supplied therefrom to the relays H and IR.

The impulse of energy supplied to the relay IR on release of the track relay is of the polarity which is effective to pick up the contact of relay IR. Accordingly, its contact 14 picks up and establishes the circuit to supply energy from the

battery FB to the track winding 11 of relay K over the section rails. This circuit is traced from the positive terminal of the battery FB over front contact 14 of relay IR, through the winding of

- 5 the track relay TR from its right-hand to its left-hand terminal, over track rail 1, through track winding 11 of relay K from its left-hand to its right-hand terminal, over back contact 10 of relay CR, track rail 2, and resistor 29 to the negative terminal of the battery FB. The energy supplied through the track relay winding flows through the winding in the wrong direction to pick up the relay contacts so they remain released at this time.
- 15 The energy supplied from the battery FB to the track winding 11 of relay K causes the contact 18 of the relay to move to its left-hand or normal position in which it establishes the circuit of the relay AR.
- 20 The impulse of energy supplied from the decoding transformer DT to relay IR is effective to maintain the relay contacts picked up for only a short period so the contact 14 releases and cuts off the supply of energy from the battery FB to
- 25 the relay K and connects the track relay TR across the section rails, and the equipment is then in the condition shown in Fig. 1 of the drawing. Before the relay IR releases, however, the contact 18 of relay K will have been moved to
- 30 its normal position, and, because of the operating characteristics of the relay, will remain in that position after the supply of energy to winding 11 is cut off.

During subsequent picked-up periods of the 35 coding relay CR the track battery is connected across the section rails, while energy is supplied to the local winding 16 of the relay K so that its contact 18 is moved to its reverse position. During subsequent released periods of the relay 40 CR the track winding 11 of relay K is connected across the section rails so that impulses of feed-back energy supplied over the section rails may feed to the winding 11 of relay K and move the relay contact 18 to its normal position.

- 45 As long as the section is vacant, therefore, the contact 18 of relay K is moved to its normal position to establish the circuit of relay AR during each released period of the contacts of relay CR. The circuit of relay AR is interrupted during each picked-up period of the contacts of relay CR, but the relay AR is of a type the contacts of which are slow enough in releasing to remain picked up during the picked-up periods of the relay CR.
- 55 Accordingly, as long as the section is vacant, contact 21 of relay AR is picked up and cuts off the supply of energy to the primary winding of the track transformer TT, while it shunts this winding to reduce the impedance of the transformer secondary winding.
- 60 When a train enters the section, the track relay remains released and energy is no longer supplied through the decoding transformer DT to the relays H and IR so that their contacts remain released, and relay IR does not establish the circuit to supply impulses of feed-back energy from the battery FB to the section rails. Furthermore, the train shunts the section rails, and the supply of feed-back energy to relay K is cut off. Accordingly, during each picked-up period of the contacts of relay CR energy is supplied to the local winding 16 of relay K and the relay contact 18 is moved to its right-hand or reverse position and is held in that position. During 70 each released period of the contacts of relay CR

the track winding 11 of relay K is connected across the section rails, but as the supply of feed-back energy over the section rails is cut off, energy is not supplied to track winding 11 of relay K and its contact 18 remains in its reverse position in which it interrupts the circuit of relay AR. The contact 21 of relay AR, therefore, releases and establishes the circuit for supplying energy to the primary winding of track transformer TT so that during the picked-up periods of relay CR energy is supplied to the section rails from the track transformer as well as from the track battery. The energy supplied from the track transformer to the section rails may control the cab signal apparatus on the locomotive of the train in the track section.

When the train passes out of the section, the impulses of master code supplied from the battery TB to the section rails feed to the track relay and operate it so that the impulse relay IR causes impulses of feed-back energy to be supplied to the section rails. The impulses of feed-back energy feed to the track winding 11 of relay K over back contact 10 of relay CR, and cause contact 18 of relay K to move to its left-hand or normal position and establish the circuit of relay AR so that its contact 21 picks up and cuts off the supply of energy to transformer TT.

In addition, as a result of the supply of master code to the track relay, energy is supplied through decoding transformer to relay H and its contacts are picked up.

This track circuit apparatus is arranged so that energy stored in the track rails as a result of the supply of impulses of master code to the section rails will not cause improper operation of the relay K. As explained above, when the contacts of relay CR are picked up, the track battery TB is connected across the section rails, while energy is supplied to the local winding 16 of relay K to move contact 18 to its reverse position in which it interrupts the circuit of relay AR. On release of the contacts of relay CR, the supply of energy from the track battery TB to the section rails is cut off, while contact 10 connects the track winding 11 of relay K across the section rails and contact 15 interrupts the circuit of winding 16.

If at this time the section is occupied, impulses of feed-back energy will not be supplied over the section rails to the track winding 11 of relay K, but energy stored in the track circuit as a result of the supply of master code to the section rails will feed to the winding 11. When coding relay contact 10 is picked up the battery TB is connected across the section rails with the positive terminal of the battery connected to track rail 1. On release of contact 10 the supply of energy from the track battery to the section rails is cut off, but because of the inductance of the track circuit energy will continue to flow therein in the same direction in which it had been flowing. Accordingly, energy will flow from rail 1 to rail 2 through the wheels and axles of the train in the section, over back contact 10 of relay CR, and through winding 11 of relay K from right to left to rail 1. The direction of flow of this energy through the winding 11 is such that it holds contact 18 of relay K in its reverse position in which it interrupts the circuit of relay AR.

When the apparatus is arranged as shown in Fig. 1, the contact of relay K will occupy its reverse position for somewhat longer periods than

it is in its normal position. This may be objectionable and in Fig. 2 we have shown means for causing the periods in which the contact of relay K occupies each of its two positions to be substantially equal.

The means for supplying energy to the coding relay CR is arranged so that the picked-up and released periods of the contacts of the relay CR are substantially equal in length. On picking up of the contacts of relay CR contact 15 establishes the circuit of winding 16 of relay K, and when the equipment is arranged as shown in Fig. 1, the contact 18 of relay K responds almost instantaneously and moves to its reverse position.

On release of the relay CR contact 10 interrupts the circuit of the track battery and connects the winding 11 of relay K across the section rails, while contact 15 of relay CR interrupts the circuit of relay K. On interruption of the circuit of the track battery the track relay releases and causes an impulse of energy to be supplied from the decoding transformer DT to relay IR so that the contact 14 of relay IR picks up and establishes the circuit for supplying energy from battery FB over the section rails to the winding 11 of relay K.

Accordingly, there is a time interval from the instant of release of the contacts of relay CR until energy is supplied over the track rails to relay K, the length of this time interval being determined by the release time of relay TR and the pick-up time of relay IR, while a further short time elapses before the relay K responds to energy supplied over the section rails.

Since the contact of relay K responds almost instantaneously on pick-up of relay CR, and as there is some delay in the response of the contact of relay K on releasing of relay CR, the contact of relay K will be in its reverse position for somewhat longer periods than it is in its normal position. In the modification shown in Fig. 2 means is provided for delaying response of relay K to energy supplied to winding 16 on pick-up of relay CR for substantially as long as is required for relay K to respond to energy supplied over the track rails to thereby equalize the periods during which the contact of relay K occupies each of its two positions.

In the modification shown in Fig. 2 an impedance in the form of a reactor 24 is connected in series with the circuit of winding 16 of relay K, while a condenser 25 is connected in multiple with the reactor 24. The apparatus of Fig. 2 is otherwise the same as that shown in Fig. 1.

When the contacts of relay CR pick up, contact 15 establishes the circuit for supplying energy to winding 16 of relay K in series with reactor 24 and condenser 25. Flow of energy through the reactor 24 to winding 16 of relay K is retarded until the flux in the core of the reactor builds up, while initial flow of energy through the winding of the reactor and also through the winding 16 of relay K is delayed while a charge is built up on the condenser 25. After the core of the reactor is saturated, energy flows freely through the winding of the reactor to the winding 16 of relay K, while the energy stored in the condenser is discharged by flow of energy between the elements of the condenser through the reactor winding.

The reactor 24 and the condenser 25 are proportioned so that the supply to the winding 16 of relay K of energy effective to move the relay contact is delayed for a period substantially equal to that which elapses from release of relay CR to

response of relay K to energy supplied over the section rails.

When the contacts of relay CR release contact 15 interrupts the circuit of the reactor 24 and of the winding 16 of relay K, and the flux in the core of the reactor 24 collapses, thereby inducing in the winding of the reactor an impulse of energy which is of the same polarity as the energy previously supplied to the reactor winding. Some of the energy induced in the reactor winding is supplied to the condenser 25 and is subsequently dissipated by flow of energy between the elements of the condenser through the winding of the reactor. The balance of the energy induced in the reactor winding on opening of contact 15 flows through winding 16 of relay K and is dissipated in the arc which forms on opening of contact 15. As the condenser 25 absorbs a substantial part of the energy induced in the reactor winding the arc which occurs on opening of contact 15 is much smaller than would be present if the condenser were not provided, and the life of the contacts is correspondingly increased.

The energy supplied from the reactor 24 to the winding 16 of relay K is of such polarity that it holds the contact 18 of relay K in the position which it already occupies, that is, its reverse position, while the impulse of energy supplied from the reactor to the winding 16 of relay K is of such short duration that the impulse terminates before energy supplied over the section rails reaches winding 16 of relay K. Accordingly, the impulse of energy supplied from the reactor to the winding 16 of relay K does not interfere with or delay response of relay K to energy supplied over the section rails.

As the modification shown in Fig. 2 includes means effective on picking up of the contacts of relay CR for delaying response of relay K for a period substantially equal to the period that response of relay K is delayed on release of the contacts of relay CR, the contact of relay K will occupy each of its two positions substantially one-half of the time, and the circuit or circuits controlled by the contact of relay K will be complete a sufficient proportion of the time to insure proper operation of the equipment energized over such circuit or circuits.

Although a reactor is shown in the circuit of the winding 16 of relay K, the invention is not limited to the use of an impedance of this type, and an impedance of another form may be employed, as for example, a resistor which restricts the flow of energy to the relay winding and thus delays building up of flux in the relay core to thereby delay response of the relay.

While the invention has been illustrated and described in connection with track circuits in which coded alternating current cab signal control energy is supplied at times to the track rails, the invention is not limited to use in such situations, but is equally applicable to track sections to which only coded direct current is supplied.

Although we have herein shown and described only one form of railway signaling apparatus embodying our invention, together with a modification which we may employ, it is understood that various changes and modifications may be made therein within the scope of the appended claims without departing from the spirit and scope of our invention.

Having thus described our invention, what we claim is:

1. In a coded railway signaling system, in com-

bination, a section of railway track through which traffic normally moves in one direction, a code following track relay at the entrance end of said section energized by current supplied over the rails of said section, a polarized code following detector relay located at the exit end of the section and having a track winding and a local winding, a coding device having contacts continuously actuated between a first and a second position, a contact of said coding device being effective when in its first position to connect the track winding of said detector relay across the section rails and being effective when in its second position to connect a track battery across the section rails, another contact of said coding device being effective when in its second position to establish a circuit to supply to the local winding of said detector relay energy effective to cause the contact of said detector relay to be moved to its reverse position, means operative on release of the track relay contacts to supply to the track rails an impulse of energy of a polarity which when supplied to the track winding of the detector relay causes the contact of said detector relay to be moved to its normal position, and an approach relay governed by said detector relay contact.

2. In a coded railway signaling system, in combination, a section of railway track through which traffic normally moves in one direction, a code following track relay at the entrance end of said section energized by current supplied over the rails of said section, a polarized code following detector relay located at the exit end of the section and having a track winding and a local winding, a coding device having contacts continuously actuated between a first and a second position, a contact of said coding device being effective when in its first position to connect the track winding of said detector relay across the section rails and being effective when in its second position to connect a track battery and the secondary winding of a track transformer in series across the section rails, another contact of said coding device being effective when in its second position to establish a circuit to supply to the local winding of said detector relay energy effective to cause the contact of said detector relay to be moved to its reverse position, means operative on release of the track relay contacts to supply to the track rails an impulse of energy of a polarity which when supplied to the detector relay track winding causes the contact of said detector relay to be moved to its normal position, and an approach relay governed by said detector relay contact.

3. In a coded railway signaling system, in combination, a section of railway track through which traffic normally moves in one direction, a code following track relay at the entrance end of said section energized by current supplied over the rails of said section, a polarized code following detector relay located at the exit end of the section and having a track winding and a local winding, a coding device having contacts continuously actuated between a first and a second position, a contact of said coding device being effective when in its first position to connect the track winding of said detector relay across the section rails and being effective when in its second position to connect a track battery and the secondary winding of a track transformer in series across the section rails, another contact of said coding device being effective when in its second position to establish a circuit to supply

to the local winding of said detector relay energy effective to cause the contact of said detector relay to be moved to its reverse position, means operative on release of the track relay contacts to supply to the track rails an impulse of energy of a polarity which when supplied to the detector relay track winding causes the contact of said detector relay to be moved to its normal position, and an approach relay governed by said detector relay contact and controlling the supply of energy to the primary winding of said track transformer.

4. In a coded railway signaling system, in combination, a section of railway track having a first and a second track rail over which traffic normally moves in one direction, a code following track relay at the entrance end of said section energized by current supplied over the section rails, a polarized code following detector relay located at the exit end of the section and having a winding having one of its terminals connected to said first track rail, a track battery having one of its terminals connected to said first track rail, a coding device having contacts continuously actuated between a first and a second position, a contact of said coding device being effective according as it is in its first or its second position to connect said second track rail to the other terminal of said detector relay winding or to the other terminal of said track battery, another contact of said coding device being effective when in its second position to supply to a winding of said detector relay energy effective to cause the contact of said detector relay to be moved to its reverse position, means operative on release of the track relay contacts to supply to the track rails an impulse of energy of a polarity which when supplied to the detector relay is effective to move the contact of said detector relay to its normal position, and an approach relay governed by said detector relay contact.

5. In a coded railway signaling system, in combination, a section of railway track having a first and a second track rail over which traffic normally moves in one direction, a code following track relay at the entrance end of said section energized by current supplied over the section rails, a polarized code following detector relay located at the exit end of the section and having a winding having one of its terminals connected to said first track rail, supply means comprising a track battery and a track transformer connected in series, one terminal of said supply means being connected to said first track rail, a coding device having contacts continuously actuated between a first and a second position, a contact of said coding device being effective according as it is in its first or its second position to connect said second track rail to the other terminal of said detector relay winding or to the other terminal of said supply means, another contact of said coding device being effective when in its second position to supply to a winding of said detector relay energy effective to cause the contact of said detector relay to be moved to its reverse position, means operative on release of the track relay contacts to supply to the track rails an impulse of energy of a polarity which when supplied to the detector relay is effective to move the contact of said detector relay in its normal position, and an approach relay governed by said detector relay contact and controlling the supply of energy to said track transformer.

6. In a coded railway signaling system, in combination, a section of railway track having a first

and a second track rail over which traffic normally moves in one direction, a code following track relay at the entrance end of said section energized by current supplied over the section rails, a polarized code following detector relay located at the exit end of the section and having a contact which is moved to its normal or its reverse position according as energy flows through a winding of the relay from its first to its second terminal or from its second to its first terminal, a coding device having contacts continuously actuated between a first and a second position, a track battery, a contact of said coding device being effective when in its first position to connect the track battery through a circuit independent of said detector relay across the section rails with the positive terminal of the battery connected to said first track rail, a contact of said coding device being effective when in its second position to connect said detector relay winding across the section rails with the first terminal of said winding connected to said first track rail, a contact of said coding relay being effective when in its first position to supply to a winding of said detector relay energy effective to move the detector relay contact to its reverse position, means effective on release of the track relay contacts to connect a source of energy across the section rails with the positive terminal of said source connected to said first track rail, and an approach relay governed by said detector relay contact.

7. In a coded railway signaling system, in combination, a section of railway track having a first and a second track rail over which traffic normally moves in one direction, a code following track relay at the entrance end of said section energized by current supplied over the section rails, a polarized code following detector relay located at the exit end of the section and having one of its terminals connected to said first track rail, means operative on release of the track relay contacts to supply to the track rails an impulse of energy of a polarity which when supplied to the detector relay is effective to move the contact of said detector relay to its normal position, a track battery having one of its terminals connected to said first track rail, a coding device having contacts continuously actuated between a first and a second position, a contact of said coding device being effective according as it is in its first or its second position to connect said second track rail to the other terminal of said detector relay winding or to the other terminal of said track battery, another contact of said coding device when in its second position establishing a circuit for supplying to a winding of said detector relay energy of a polarity effective to move the relay contact to its reverse position, said circuit having an impedance associated therewith which delays response of said detector relay to energy supplied over said circuit for a period substantially equal to the period from movement of the coding relay contacts to their second position until response of the detector relay to energy supplied over the track rails, and an approach relay governed by said detector relay contact.

8. In a coded railway signaling system, in combination, a section of railway track having a first and a second track rail over which traffic normally moves in one direction, a code following track relay at the entrance end of said track section energized by current supplied over the section rails, a polarized code following detector re-

lay located at the exit end of the section, means operative on release of the track relay contacts to supply to the track rails an impulse of energy of a polarity which when supplied to the detector relay is effective to move the contact of the detector relay to its normal position, a coding device having contacts continuously actuated between a first and a second position, a contact of said coding device being effective when in its second position to establish a circuit to supply to a winding of said detector relay energy effective to move the contact of said relay to its reverse position, another contact of said coding device being effective when in its second position to connect a track battery across the section rails through a circuit independent of the winding of said detector relay, a contact of said coding device being effective when in its first position to connect a winding of said detector relay across the section rails, and an approach relay governed by said detector relay contact.

9. In a coded railway signaling system, in combination, a section of railway track having a first and a second track rail over which traffic normally moves in one direction, a code following track relay at the entrance end of said track section energized by current supplied over the section rails, a polarized code following detector

relay located at the exit end of the section, means operative on release of the track relay contacts to supply to the track rails an impulse of energy of a polarity which when supplied to the detector relay is effective to move the contact of the detector relay to its normal position, a coding device having contacts continuously actuated between a first and a second position, a contact of said coding device being effective when in its second position to establish a circuit to supply to a winding of said detector relay energy effective to move the contact of said relay to its reverse position, said circuit having associated therewith means for delaying response of said detector relay to energy supplied over said circuit for a predetermined period subsequent to establishment of said circuit, another contact of said coding device being effective when in its second position to connect a track battery across the section rails through a circuit independent of the winding of said detector relay, a contact of said coding device being effective when in its first position to connect a winding of said detector relay across the section rails, and an approach relay governed by said detector relay contact.
